UNITED STATES PATENT OFFICE.

CLAUDE C. NUCKOLS, OF MENANDS, NEW YORK.

BASE-BOARD-CONCEALED RADIATOR.

1,301,589.

Specification of Letters Patent. Patented Apr. 22, 1919.

Application filed June 7, 1915. Serial No. 32,636.

To all whom it may concern:

Be it known that I, CLAUDE C. NUCKOLS, a citizen of the United States, and a resident of Menands, county of Albany, State of New York, have invented certain new and useful Improvements in Base-Board-Concealed Radiators, of which the following is a specification.

My invention relates to baseboard concealed radiators and particularly to such radiators which are located wholly within the wall of a room in such a way that a suitable grille plate may be substituted for the ordinary baseboard, without extending out into the room.

I am aware that it has been heretofore proposed to conceal radiators behind something in the nature of a baseboard, but so far as I am aware, none of these attempts have been of practical value, due to structural and other defects. It is an object of my present invention to provide an arrangement whereby the radiator may be concealed wholly within the wall, without in any way weakening the wall structure.

Another object of my invention is to provide the grille plate, which takes the place of the ordinary baseboard, with an outwardly and downwardly projecting lip at the top thereof, which lip serves to deflect particles of dirt which may be carried by the heated air, and thus prevent their being disseminated through the room.

My invention consists broadly in providing a channel-shaped member or members secured at the bottom to the floor and at the top to the lower ends of the ordinary wall studs. These channel-shaped members, which are preferably of metal, thus in a sense form a continuation of the wall studs, and the channeled surfaces thereof which face toward the room provide a convenient receptacle for the radiator.

In the drawings,

Figure 1 represents a perspective view of a portion of a room, showing the means whereby the radiator may be located within the wall;

Fig. 2 is an elevation of a portion of a completed wall, showing the grille plates in position to conceal the radiators;

Fig. 3 is a sectional view of a completed wall, showing the grille plate in position;

Fig. 4 is a front view of the parts shown in Fig. 3 with the grille plate removed, and

Figs. 5 and 6 are views similar to Figs. 3 and 4 respectively, but showing a slight modification of my invention.

Referring to Fig. 1, 10 indicates a radiator which may be of any desired type. In order that this radiator may be located wholly within the wall of the room, I provide channel-shaped members, such for example as shown at 11, which members are secured at the bottom to the floor 12 and are secured at the top to the various wall studs 13. These members 11 are positioned so that their channeled surfaces face toward the room and are adapted to receive the radiator 10 therein. Any suitable means may be employed for securing the tops of the members 10 to the lower ends of the studs 13, but as herein shown, I have provided the members 11 at the top with spaced upstanding flanges 14 (see Fig. 4) adapted to receive therebetween and to be secured to the studs 13.

As shown in Fig. 1, there is provided below the window opening 15 a space 16 which is entirely free from wall studs and which therefore provides a convenient receptacle for a considerable portion of the radiator, without the necessity of the installation of any such devices as the members 11.

Having secured the members 11 to the floor and to the lower ends of the wall studs, it remains merely to complete the wall above the radiator in the desired manner, as by plastering, and then to secure to the wall in place of the usual baseboard a suitable grille plate, such as is shown at 17. If the radiator is carried up into such a space, as is shown at 16, a suitable grille plate, such as 18 is provided to cover this portion of the radiator.

The grille plates 17, as clearly appears from the drawing, are substantially flush with the wall and effectively conceal the radiator without extending out into the room. At the top of the grille plate 17 I have provided an outwardly and downwardly projecting lip 19 so that as the heated air passes up over the radiator and out into the room it impinges against the lip 19, whereby the dust particles carried by the heated air are deflected down on to the floor, instead of being disseminated through the room.

The modification of my invention illustrated in Figs. 5 and 6 contemplates the use

of a continuous channel bar on each side of the room in place of the individual channeled members for the various studs. In carrying out this modification I secure to the 5 top of each channel bar 20 a nailing strip of wood, such as indicated at 21, to provide means whereby the various studs 13 may be secured thereto. In other respects the modification is similar to the embodiment of my 10 invention previously described and therefore need not be discussed in detail. Practically the only difference between the two modifications is that in the first modification I use a plurality of separate channel-shaped members, and in the second modification I use 15 a single continuous member, and that I have found it convenient to adopt different means in each case for connecting the studs to the channel-shaped members.

20 From the above description, it is apparent that I have provided means for concealing a radiator within a wall without utilizing any of the room space and without in any way weakening the wall structure of the 25 building. On the other hand, it is apparent that, whether I use an individual channel-shaped member for each stud as shown in Fig. 1, or a continuous channel-shaped member, as shown in Figs. 5 and 6, the metallic 30 channel-shaped member or members form a continuation of the wooden studs and thus increase the strength and stability of the building. Also attention is directed to the neatness of appearance of the completed 35 wall, the same being a decided improvement over exposed radiators and over all attempts at concealing radiators of which I am aware.

While I have shown and described but two embodiments of my invention, I do not 40 wish to limit myself to any particular embodiment thereof, since obviously many changes may be made therein, without departing from the spirit of my invention.

What I claim is:

45 1. As an article of manufacture a casing for concealing a radiator within the wall of a room, comprising in combination, a channel-shaped member the bottom of which is secured to the floor and the top of which is 50 secured to the lower end of a wall stud

thereby forming a continuation of the latter, said channel-shaped member being so positioned that it lies wholly within the wall with its channeled surface facing toward the room and adapted to receive the radiator therein; a grille plate secured in position substantially flush with the wall and overlying the channel-shaped member and radiator; and an outwardly and downwardly projecting lip secured to said grille plate 60 near the upper and outer edge thereof.

2. As an article of manufacture a casing for concealing a radiator within the wall of a room, comprising in combination, a channel-shaped member the bottom of which is 65 secured to the floor and the top of which is secured to the lower end of a wall stud thereby forming a continuation of the latter, said channel-shaped member being so positioned that it lies wholly within the wall 70 with its channeled surface facing toward the room and adapted to receive the radiator therein; a grille plate secured in position substantially flush with the wall and overlying the channel-shaped member and radiator, 75 said grille plate being in spaced relation with respect to the floor to provide a substantially continuous opening adjacent said floor; and an outwardly and downwardly projecting lip secured to said grille plate 80 near the upper and outer edge thereof.

3. Means for concealing a radiator within the wall of a room, comprising a channel-shaped member, the bottom of which is secured to the floor and the top of which is 85 provided with a pair of spaced upstanding flanges, adapted to receive therebetween and to be secured to the lower end of a wall stud, said channel-shaped member being so positioned that it lies wholly within the wall 90 with its channeled surface facing toward the room and adapted to receive the radiator therein.

In testimony whereof I have signed this specification in the presence of two subscribing witnesses:

CLAUDE C. NUCKOLS.
